UNITED STATES PATENT OFFICE.

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY.

APPARATUS FOR THE TRANSFORMING OF HEAT.

Application filed May 5, 1926. Serial No. 106,825.

This invention relates to heat transforming apparatus, and more particularly to apparatus which is adapted and intended for use with the lubricating working substances 5 of the type disclosed and claimed in my copending application, Serial No. 60,311—filed October 3, 1925.

One object of the invention is to provide apparatus which will successfully utilize 10 lubricating working substances in the transforming of heat. Another object is to provide such apparatus operating with the crank case of the compressor at approximately atmospheric pressure. Another object is to utilize the crank case of the compressor as a part of the refrigerant circuit. Other objects will be apparent from the detailed description which follows:

The single figure of the drawing represents somewhat diagrammatically a refrigerating system of the closed cycle type, certain parts of which are shown in section.

The embodiment of the invention chosen for the purpose of illustration consists essentially of an evaporator or refrigerating element 1 intended to be mounted in a refrigerating compartment diagrammatically indicated at A, a pump or compressor 2, a condenser 3, and a suitable feeding or expansion device 4 for regulating the passage of condensed refrigerant into evaporator 1. The parts specified are connected as indicated to form a closed cycle system utilizing a lubricating refrigerant such as described 30 in my copending application, Serial No. 60,311, filed October 3, 1925 and operating in general in accordance with the process disclosed in my copending application, Serial No. 85,580, filed February 2nd, 1926.

To effect the necessary concentration of the working substance to enable it to be used for lubricating purposes, evaporator 1 is provided with a concentrating chamber 1^a arranged to be disposed at the top of the refrigerating compartment A. The inlet 1^b to the concentrating chamber and the outlet connection 5 to compressor 2 are so disposed as to permit a body of lubricating refrigerant to remain in chamber 1^a while the more volatile portions thereof vaporize. The vaporized refrigerant and a part of concentrated lubricant mixture are drawn from chamber 1^a by the action of compressor 2 through inlet valve 2^a into the piston chamber of the compressor, whence they are dis-

charged at a higher temperature and pressure through a discharge valve 2^b in the compressor piston into crank case 2^c. As the concentrated lubricant mixture is splashed about in the crank case to lubricate the moving parts of the compressor, some of it enters conduit 6 which leads from the upper part of crank case 2^c to condenser 3 where it is diluted by the condensed vapor and passes through connection 7 and expansion device 4 back into evaporator 1.

The apparatus described above may be placed in operation by putting pure lubricant (for example, vaseline) in the crank case 2^c, and pure refrigerant (for example, methylene chloride) in evaporator 1 and into the concentrating chamber 1^a. Upon starting the compressor 2, some of the refrigerant is carried over into the crank case, diluting the lubricant therein. This dilution continues down to a certain concentration dependent upon the temperature in the crank case; the warmer the temperature, the less is the dilution. When the mixture in the crank case becomes constant (usually comprising 15 to 20% of vaseline) which may require the addition of more refrigerant from time to time, the mixture in the crank case begins to overflow or to be splashed into conduit 6 whence it passes into condenser 3 and is diluted by the condensate of the refrigerating vapor down to a liquid mixture containing perhaps 3% of vaseline. The mixture then passes through the expansion device 4 into evaporator 1 where it begins to concentrate as the refrigerant is vaporized. The concentrating liquid rises through evaporator 1 and overflows through inlet pipe 1^b into the concentrating chamber 1^a where it lies quiescent and is subjected to the action of compressor 2 and to the highest temperature in refrigerating chamber A which causes the more volatile parts thereof to vaporize. There the mixture reaches a highly concentrated state and gradually passes along with the vaporized refrigerant through connection 5. Before dilution can occur the concentrated lubricant mixture is discharged into crank case 2^c, thus completing the circuit.

From the above it will be apparent that the mixture concentrated in the refrigerating zone, as in chamber 1^a, is taken directly into the cylinder of the compressor and discharged therefrom directly into the crank

case at a higher temperature and pressure, and since the temperature rises with the pressure the concentration is not readily altered so that the mixture in crank case 2⁵ remains sufficiently viscous to serve as lubricant. It is, of course, desirable to operate the compressor with the crank case warm to prevent condensation of the refrigerant vapor and an undue dilution of the mixture in 10 the crank case, and any known or desired means may be used for this purpose.

The above described arrangement offers an additional advantage when the working substance contains a gaseous incondensable 15 component operating in accordance with the process described and claimed in my copending application, Serial No. 15,172, filed March 12, 1925, since the high side pressure of such a system closely approximates atmospheric pressure and leakage from the 20 crank case is greatly reduced and readily controlled.

While one form of the invention has been herein shown and described, it is to be understood that the invention is not limited 25 to the specific details thereof but covers all changes, modifications and adaptations within the scope of the appended claims.

I claim as my invention:

30 1. In a heat transforming system of the closed cycle type utilizing a lubricating working substance, in combination, an evaporator having means for permitting concentration of the lubricating component of 35 the working substance, a compressor having a crank case, and means whereby the compressor withdraws the working substance both as vapor and as concentrated liquid from said evaporator and discharges the 40 same into said crank case.

2. In a heat transforming system of the closed cycle type utilizing a lubricating working substance, in combination, an evaporator providing a plurality of evaporating 45 bodies arranged to permit concentration of the lubricating component of the working substance, a compressor having a crank case, a connection from said evaporator to the inlet of said compressor arranged to pass

some concentrated liquid along with the 50 gaseous contents of said evaporator, and means directing the discharge of said compressor into the crank case thereof.

3. In a refrigerating system utilizing a lubricating refrigerant, an evaporator having means for permitting concentration of the lubricating component of the working substance, a compressor having a crank case, means by which said compressor withdraws vapor from said evaporator along with concentrated lubricant and discharges the same 55 into said crank case, a condenser connected to said crank case, and a connection from said condenser to said evaporator thereby to form a closed cycle system.

4. In a refrigerating system for utilizing a refrigerating solution, an evaporator having means for concentrating said solution and providing a series of bodies of the solution, a compressor having a higher pressure 70 part and a lower pressure part, means permitting said compressor to withdraw vapor from said evaporator along with concentrated solution and discharge both into said higher pressure part, a condenser connected 75 to said higher pressure part, and a connection from said condenser to said evaporator thereby to form a closed cycle system.

5. In a refrigerating system of the closed 80 cycle type arranged to operate on the vapor-gas principle and utilizing a refrigerant solution, an evaporator providing a series of bodies of the solution subjected to different refrigerating temperatures for concentrating 85 said solution, a compressor having a higher pressure part and a lower pressure part, means permitting said compressor to withdraw vapor from said evaporator along with concentrated solution and discharge both 90 into said higher pressure part, a condenser connected to said higher pressure part and a connection from said condenser to said evaporator.

Signed by me at Detroit, Wayne County, Michigan, this 29th day of April, 1926.

RANSOM W. DAVENPORT.
